UNITED STATES PATENT OFFICE.

HAROLD M. PLAISTED, OF ST. LOUIS, MISSOURI, ASSIGNOR OF FORTY-NINE ONE HUNDREDTHREE TO WILLIAMS PATENT CRUSHER & PULVERIZER COMPANY, OF ST. LOUIS, MISSOURI, A CORPORATION OF MISSOURI.

CRUSHER AND PULVERIZER.

Application filed July 19, 1920. Serial No. 397,424.

To all whom it may concern:

Be it known that I, HAROLD M. PLAISTED, a citizen of the United States, residing at St. Louis, State of Missouri, have invented 5 certain new and useful Improvements in Crushers and Pulverizers, of which the following is a specification.

This invention relates to certain new and useful improvements in crushers and pulverizers, the peculiarities of which will be hereinafter fully described and claimed.

The main object of my invention is to provide a crusher having means to guard an outlet passage leading to a chamber for the reception of metal pieces that may be mixed with the feed or other material being ground,—such guarding means being adapted to prevent the discharge of the ordinary feed but to allow the exit of pieces 20 of metal that may be mixed with the feed; another object is to provide a cage in sections that can be readily inserted or removed through the side of the crusher, and secured in place; another object is to provide a top wall that is removable to give access to the guarding means of the outlet passage, and also to the interior of the casing of the crusher.

In the accompanying drawing on which 30 like reference letters indicate corresponding parts, Fig. 1 represents a vertical sectional view transverse to the shaft; Fig. 2 a similar sectional view on the line 2—2 of Fig. 1; Fig. 3 a side elevation of a crusher 35 exemplifying my improvements; Fig. 4 a detail plan view of one section of my cage; and Fig. 5 a partial section illustrating the method of inserting the cage into the crusher.

40 The letter A. indicates the shaft of a crusher provided with hammers B of any suitable style pivotally mounted on discs C or other hammer supports. The casing is provided with a hopper D, and side walls E in which are formed arcuate slots F concentric with the shaft A and extending from a breaker plate G at the mouth of the hopper around towards the back, as shown in Figs. 1 and 3. This arcuate slot is 45 spanned by side webs H of the shaft bracket I on which the bearing is mounted, and

in these side webs H are openings J Fig. 2, that allow the passage past the walls H of the projecting ends or lugs K of each section of a cage, the preferred form of which 55 consists of side frame pieces L curved to conform to the arcuate slot F and connected by cross bars M having openings between them according to the fineness the material is desired to be crushed. The bars are preferably connected with each other by webs N of lesser radial depth than the bars that cross brace them as shown in Fig. 1, Fig. 2 and Fig. 4 at the bottom or outer portion of the bars only, so as not to lessen the effective length of the inner cutting edges of the bars. Three or more bars are in each section and the section is preferably formed 60 in one integral casting with the tops of the bars M chilled to improve the wearing qualities. The ends K projecting from the side pieces L are provided with holes O through which are passed pin-keys P that are long enough to engage the wall E on both sides of the slot F as shown in Fig. 3 and Fig. 2, 65 and prevent the sectional cage from shifting laterally. The side piece L is preferably a little wider than the bars M, and when in place in the arcuate slot, the sidepieces act 70 as fillers to close up the arcuate openings and present a flush appearance on each side of the casing except for the projecting lugs K that receive the pins. This lug is not the full radial depth of the side piece but is located at or near the upper edge of said piece 75 to facilitate insertion of the sectional cage into the crusher by means of a hooked bar Q Fig. 5, which engages the opening O and bears on the side of one slot as the sectional cage is inserted through the other slot as 80 shown in Fig. 5. The hooked bar Q supports the entering end of the sectional cage and readily draws it into its closing position as shown in Fig. 2.

Whenever it is necessary to remove one 85 of the cage sections the key-pins are loosened by a tap of the hammer and taken out, and, except when the bracket wall H is opposite a cage section, the section may be readily drawn out laterally. For removing a section 90 opposite the wall H it is only necessary to take out one of the other sections and slide

the first named section into position for withdrawing it. The same method is used for inserting the sectional cage.

The back wall R Fig. 1, is set away from the cage to allow free discharge of the material through the cage openings between the bars, and is curved forward to meet the top cover, the position of which is directly over the cage and rotor. This top cover consists of a removable curved top wall S resting on a shoulder T Fig. 2, and fitting against the wall of the hopper D at one end, and into a notch at the bottom end adjacent to the cage. The cover is secured by cross rods T', bearing on the cover to hold it in place and yet allow of it being readily removed in order to give access to a hinged door U, pivotally mounted at its lower end by a rod V and guarding an outlet in the upper wall W of the disintegrating chamber above the rotor, which wall meets the rear wall 3 of the hopper D. The partition wall W, the wall 3, and the cover S, together with the sides of the casing, form a chamber above the rotor with which the outlet passage 4 guarded by the door U, communicates. A vertical partition 5 adjacent to the door provides an opening 6 between its upper edge and the top wall S, over which metal pieces are thrown by the hammers when they are driven against the hinged door U and throw said door upwardly as indicated by dashed lines Fig. 1. Gravity or other means cause the door to drop back automatically upon a lip 7 at one end of the wall W, until another piece of metal is driven with force against the door and causes it to rise to permit the exit of said metal piece. The weight of the door U is sufficient to deflect the regular feed material so that it will pass the opening and be directed by the wall W around to the breaker plate once more. The curved wall R extends forward horizontally to form a stop bar 8 for the cage at the end of the arcuate slots, and also to protect the pivot of the door U from impact of metal that may break the hinge.

The partition wall W above the rotor is preferably curved eccentric to the shaft with an increasing space between the hammer circle and the said wall in the direction of motion. This eccentric curve tends to prevent the lodgment of material against the wall as it is deflected around to the breaker plate. A slide 9 on the wall 3 of the hopper regulates the opening at the bottom of the hopper. In the side walls opposite the metal catcher chamber are openings 10 protected by covers 11 to allow of clearing out the said chamber.

Any space left at the end of the arcuate slot after the cage sections have been located therein is taken up by a filler strip 12 that causes the sections to bear on each other and

against the stop bar 8 at the end of the slot. 65 The key at each end of the section forms a shoulder on the outside at each end to maintain the cage in its located position.

I claim:

1. A crusher having a casing with a partition forming upper and lower chambers, and a rotor hammer in said lower chamber,—said partition including a swinging door, pivoted at its lower end and substantially concentric with the path of travel of said 75 hammer.

2. A crusher comprising a rotor, a casing having side, top, and partition walls forming a disintegrating chamber and an upper chamber adjacent to said rotor,—the partition wall being adjacent to the rotor circle, and having an opening communicating with said latter chamber,—and an inclined door pivoted at the lower edge of said opening and in line with said partition wall, the casing having a bar located near the lower edge of said door and protecting the pivot, substantially as described. 80

3. A crusher comprising a casing having side, top and partition walls forming a rotor chamber and also a chamber above the rotor chamber,—said partition wall having an opening into the upper chamber,—and a door pivoted by one edge in said opening and opening upward,—said top wall limiting the upward movement of said door so that it will gravitate to its closed position, substantially as described. 90

4. A crusher comprising a casing having arcuate slots through the sides, a cage in sections located in said slots and having lugs with holes projecting beyond the sides of the casing, and key pins in said holes bearing on the outside of the casing adjacent to the slots, substantially as described. 100

5. A crusher comprising a casing having arcuate slots through the sides, bracket walls spanning said slots and having opening opposite said slots, a cage in sections mounted in said slots and having lugs provided with holes projecting beyond the sides of the casing and slidable circumferentially to their located position, key pins in said holes to prevent endwise movement of said sections, and a filler key passing through said slots 110 and securing the sections against lateral displacement. 115

6. A crusher comprising a casing having arcuate slots through the sides, a cage in sections adapted to enter endwise said slots and each section having a lug on the entering end projecting outside the casing and provided with a radially transverse hole and a key pin in said hole located transversely to said slot and engaging the casing near the inner and upper face of each section. 120

7. A crusher comprising a casing having arcuate slots through its sides, a cage formed

- in sections mounted in said slots,—each section consisting of side frames curved to conform to the arcuate slots and substantially closing said slots when in located position
5 and spaced cross bars connecting said curved frames,—the said bars having a lesser radial depth than the frames and providing clearance to facilitate mounting the sections, and means to secure said sections.
- 10 8. In a crusher of the kind described, a sectional cage, each section consisting of integral curved sides and spaced connecting bars having intermediate integral connecting webs of lesser radial depth than the bars
15 and located away from the inner grinding

face and connecting the bottom portion of the bars.

9. A crusher comprising casing walls forming a disintegrating chamber and a partition forming an upper chamber with a door-
20 guarded communicating opening,—the side walls of the casing extending above the partition wall,—and a removable cover for the upper chamber mounted between the side walls, and means to hold said cover in place
25 but allowing of removal to give access to said upper chamber.

In testimony whereof I have affixed my signature.

HAROLD M. PLAISTED.
